CABINET FOR COVERING LAVATORY PIPES

Ulysses Harris, Westfield, N.J., assignor to
Ten-O-Feb., Inc., Westfield, N.J.

Filed Dec. 20, 1973, Ser. No. 426,803

Term of patent 3½ years

Int. Cl. D6—04; D23—02
U.S. Cl. D23—59

FIG. 1

FIG. 2

FIG. 3

FIG. 4

FIG. 5

FIG. 1 is a perspective view of a cabinet for covering lavatory pipes, showing my new design.

FIG. 2 is a perspective view thereof, with the door shown opened.

FIG. 3 is a rear view of the design as shown in FIG. 1.

FIG. 4 is a sectional view taken on lines 4—4 of FIG. 3.

FIG. 5 is a bottom view thereof, as shown in FIG. 1. The broken line showing of a lavatory and portions of a wall in FIGS. 1 and 2 are of illustrative purposes only and form no part of the claimed design.

I claim:

The ornamental design for a cabinet for covering lavatory pipes, as shown and described.
